GALLERY CONSTRUCTION FOR DOUBLE-DECK RAILWAY CARS

Albert G. Dean, Narberth, Pa., assignor to The Budd Company, Philadelphia, Pa., a corporation of Pennsylvania

Application August 10, 1951, Serial No. 241,196

5 Claims. (Cl. 105—340)

1

The invention relates to improvements in the construction of the gallery of so-called gallery railway cars, that is: double-deck cars having the second deck in the form of galleries or balconies arranged along the side walls and leaving an open space between them.

The aforesaid type of car is disclosed in an application of Joseph F. Clary, Double-Deck Railway Passenger Car, Serial No. 217,663, filed March 26, 1951, as a continuation-in-part of the original application, Railway Passenger Car, Serial No. 764,289, filed July 29, 1947, now abandoned.

The object of the invention is a construction which combines great strength with light weight, which facilitates movement of the passengers to and from their seats, and which allows convenient communication between passengers on the gallery and a railroad conductor walking along the aisle of the main floor in checking and collecting tickets or fares.

The invention achieves these and other objects and advantages by the formation of the gallery railing as an open latticework truss girder and as main support for the inner margin of the respective gallery floor.

The new construction dispenses with supporting stanchions between the lower main deck and the inner margin of the gallery deck, stanchions which would impede the movement of passengers to and from their seats on the main floor.

The new construction also permits relieving the roof from any substantial stresses as compared with constructions having the inner gallery margin suspended from the roof by means of hangers. Such hangers, if provided at all in the new construction, have the only function of laterally stabilizing the gallery railing.

The new construction, due to its open latticework, permits the conductor walking on the main floor to reach through the openings of the railing in checking, collecting, or distributing tickets and fares for passengers on the gallery.

Due to its relatively great height, the gallery railing has great supporting strength, even if manufactured of relatively light metal tubing, and contributes, therefore, to keeping down the overall weight and manufacturing expense for the whole car.

Further features and details, objects and advantages of the invention, will become apparent from the following description of one embodiment, which is illustrated in the attached drawing.

In the drawing:

Fig. 1 is a fragmentary, diagrammatic, longi-

2

tudinal section through slightly more than one-half of a gallery car;

Fig. 2 is a horizontal section and plan view, on a smaller scale, of the entire car, the approximate plane of section being indicated by line 2—2 of Fig. 1;

Fig. 3 is a transverse section, on a larger scale, substantially along line 3—3 of Fig. 1;

Fig. 4 is a fragmentary perspective, on a still larger scale, from about the center of the car toward one end thereof;

Fig. 5 is a fragmentary, large-scale section through the righthand railing of Fig. 3 and of adjoining portions of the gallery floor and the ceiling structure;

Fig. 6 is a horizontal, large-scale, fragmentary section through one end of the railing and one of the end wall panels; and

Fig. 7 is a large-scale, fragmentary side elevation of the connection between the upper part of the railing to the end wall.

The illustrated car has a main deck and underframe structure 10, end walls 11, side walls 12, and a roof 13. The entire car is of the type in which underframe, side walls, and roof constitute together a hollow-section beam which transfers the load to the supporting trucks, indicated by the wheels 14 in Fig. 1, and takes up the compression and draft stresses.

The end walls 11 are provided with door openings and doors 15 for communication with adjoining cars (Figs. 1 and 14). The side walls 12 each have a central entrance opening and doors 16 combined with step well 17 (Fig. 1). On both sides of the vestibule interconnecting side doors 16 are arranged stairs 18 along each of the side walls. These stairs lead to the galleries 19, each of which extends between one of the stairs 18 and an end wall 11. The side walls are provided with two rows of windows 20, one below the gallery and the second above the gallery. A row of double seats 21 is arranged on either side of a central aisle 22 of floor 10 and a row of single seats 23 on each gallery 19 along the respective side wall 12. Each gallery ends at the respective stair with its newel post 24.

These rather diagrammatically illustrated and briefly described general arrangement and construction of the car are substantially similar to those disclosed in the aforesaid application Serial No. 217,663.

The outer margins of the gallery floor 25 are supported through brackets or sill structures 26, the latter being secured to the respective side walls 11. A raised floor portion 27 has its outer

margin likewise supported by the side wall 11 and its inner margin at 28 by the mid-portion of floor 25. Floor portion 27 carries the seats 23, while the inwardly projecting portion of floor 25 provides for a relatively high aisle between it and roof 13.

The inner margin of floor 25 is supported by a double-walled panel structure 29 which constitutes the so-called decency panel. The lower margin of structure 29 is reinforced at 30 and telescopingly receives and is secured to the inner margin of floor 25. Structure 29 is at certain intervals additionally reinforced in its interior by vertical braces 31 inserted between its panels 32, 33. Said panels form the main elements of structure 29, and their upper margins telescopingly receive and are structurally connected to a box-sectional beam or tube 34. Tube 34 constitutes the lower chord member of the gallery railing which, in addition, is composed of tubular upper chord member 35 and diagonal struts 36 interconnecting chords 34, 35. Upper chord 35 serves simultaneously as hand rail and is provided for this purpose with a top molding 37.

The lower panel structure 29, as well as the railing have their ends structurally tied into one end wall 11 and one newel post 24. The tie-in of the railing to newel post 24 is by means of an inward projection 38 of the latter, which in turn ties into a transverse structure 39 extending between the side walls under the roof in the central region of the car.

End wall 11 has an inner panel 40 supporting a hat-section 41. Secured to section 41 is the end of upper chord member 35 and of end strut 36 by means of brackets 42 and gussets 43, as shown in Figs. 6 and 7. Panel structure 29 and lower chord member 34 are similarly tied into panel 40 and hat-section 41, the hat-sections for opposite gallery flanking the passage door 15, Fig. 4. The other end of railing and panel structure is similarly tied into projection 38 of the newel post.

Lateral stability of the gallery railing is increased by tubular hangers 44 which extend between upper chord member 35 and structure 45, which latter projects downwardly from the roof and constitutes part of the air-conditioning and lighting arrangements. Supported by the hangers 44 is a shelf 46 below structure 45, the shelf providing small luggage compartments for the gallery passengers.

Certain features of the illustrated and described embodiment are also shown and described in application Lewis F. Reynolds and Norman W. Fesmire, for Air-Conditioning Means for Vehicles, Serial No. 241,216, filed August 10, 1951, simultaneously with the present application.

The invention is not restricted to the details of the illustrated embodiment but is susceptible to modifications and adaptations which will easily occur to those skilled in the art.

What is claimed is:

1. In a double-deck railway car having a body structure including side walls and having an upper deck in the form of galleries extending along and inwardly from said side walls, gallery floors, railings along the inner margins of said galleries, said railings being formed as open latticework truss girders having their ends structurally connected with and supported by said body structure, said railings supporting the inner margins of the gallery floors.
2. In a double-deck railway car: side walls, a roof, a floor, and longitudinally spaced upright supporting structures, such as end and partition walls; an upper deck in the form of a gallery extending inwardly from and along one of said side walls between two of said upright structures, said gallery having a floor and a railing along the inner margin of said floor; said railing being largely in the form of an open lattice truss having upper and lower chords interconnected by struts, the ends of said truss being structurally secured to and supported by said upright structures, and means along the lower margin of said truss structurally and supportingly interconnecting it with the inner margin of said gallery floor.
3. In a double-deck railway car according to claim 2: said means interconnecting said railing truss and the inner margin of the gallery floor, being in the form of a panel structure serving simultaneously for hiding from view the lower parts of the bodies of gallery occupants from the gaze of persons on the main deck of the car.
4. In a double-deck railway car according to claim 2: said means interconnecting the railing truss and the inner margin of the gallery floor, being in the form of a hollow, double-walled panel structure comprising transversely spaced panels, said truss having its lower chord telescopingly received between and structurally secured to said panels.
5. In a double-deck railway car: side walls, a roof, a floor, longitudinally spaced vertical supporting structures, an upper deck in the form of a gallery extending inwardly from and along a side wall between two of said upright structures, at least one being formed by a newel post of a stair leading to said gallery, said gallery having a floor and a railing along the inner margin of said floor, said railing being largely in the form of an open lattice truss, the ends of said truss being structurally secured to and supported by said newel post and the second one of said upright structures, and means along the lower margin of said truss girder structurally interconnecting the latter with the inner margin of said gallery floor so as to form the inner support for said floor.

ALBERT G. DEAN.
